Specification of Letters Patent.

Patented May 14, 1918.

Application filed April 9, 1914. Serial No. 830,645.

To all whom it may concern:

Be it known that we, GEORGE A. HOWARD and GEORGE L. SLATER, both citizens of the United States, and both residing at Buchanan, in the county of Berrien and State of Michigan, have jointly invented new and useful Improvements in Perambulators, of which the following is a full, clear, concise, and exact description, reference being had 5 to the accompanying drawing, forming a part of this specification.

Our invention relates to improvements in perambulators.

It is one of the principal objects of our 15 invention to provide a device of the class described and which may at times be used also as a chair.

It is a further object of our invention to provide such a device in which the change 20 from one use to another is easily and quickly made.

It is a further object of our invention to provide such a device in which efficient support is given both laterally and otherwise 25 when the device is used as a chair.

It is a further object of our invention to provide such an article that is economical to manufacture, efficient in use and attractive in appearance.

30 Further objects and benefits of our invention will be apparent from the following description and accompanying drawings taken in connection with the appended claims.

We have described in the following specification and illustrated in the accompanying drawings a perambulator disclosing our invention by way of example, it being clearly understood that numerous changes may be made in the form, construction and arrangement 35 of the parts without departing from the spirit of our invention or exceeding the scope of the appended claims, the form of the invention herein disclosed being merely one preferred embodiment thereof.

40 In the drawings:

Figure 1 is a view in side elevation of a perambulator constructed in accordance with our invention;

Fig. 2 is a similar view showing the device 50 used as a high-chair;

Fig. 3 is a front elevation of the same;

Fig. 4 is a detailed view in rear elevation showing the operating mechanism;

Fig. 5 is a detail in perspective showing the seat member; and

Fig. 6 is a detail in perspective showing the removable tray.

Like reference characters refer to like parts throughout the following specification and the several figures of the accompanying 60 drawings.

Referring now to the drawings, the perambulator comprises in general a light metal skeleton framework having a pair of large wheels suitable for perambulator purposes, and a chair member. This framework has on either side forward and rear uprights 7, 8. These uprights are connected at their lower ends by a brace 9, to which each is riveted. At their upper ends the uprights are curved in to meet at a common point, and the two pair are connected by a wooden bar or handle 10 by which the perambulator is propelled. Connecting the rear uprights 8, and riveted thereto, is an 70 upper cross-bar 11 and a lower cross-bar 12. The framework is further strengthened by a transverse brace 13 connecting the forward uprights 7 near the bottom thereof. Connecting the upper and lower cross-bars 75 10 and 11 are two braces 14, 15, which are riveted at their ends to the cross-bars. Bearing in the brace member 9 is an axle 16 to which a pair of perambulator wheels 17, 18 are attached.

The chair member (Fig. 5) comprises a seat 19, a back 20, a foot-rest 21 and arms 22. The arms 22 are bolted to supports 23 which are in turn bolted to the seat 19. Downwardly extending brackets 24 support 90 the foot-rest 21. The seat 19 and back 20 are preferably provided with leather or padded cushions 25, 26. Secured to the back 20 at either side thereof and extending forwardly, is a yoke 27 embracing a pin 27^a 95 on the arm 22 and forming therewith a sliding pivotal connection between the back and the arms, the function of which is herein-after referred to.

It will be noted that in this embodiment 100 of our invention the chair member, comprising the seat, back, arms and foot-rest is a unified structure, separate from and independent of the framework. It is of such dimensions as to fit between the uprights 105 and it is supported on the framework in

upper or lower positions, as will hereinafter appear.

At the rear end of each arm 22 is a hook 28 adapted to fit over either cross-bar 11 or 5 12. When it is desired to use the device as the usual perambulator, or a low chair, the chair member is hung on the lower cross-bar 12 (Fig. 1). In this position the forward part of the chair member is supported 10 by the transverse brace 13. Associated with the latter is a flat spring 13^a which is of substantially the same length as the brace 13, and which is riveted to the same at each end (Fig. 3). The spring is held over the 15 brace 13 by bolts 13^b which slide up and down in suitable apertures in the brace as the spring is depressed or extended. As the seat rests on this spring the shocks and jars which would otherwise make the seat uncomfortable are largely taken up by the action 20 of the spring.

Auxiliary means are provided for giving the device stationary support, temporarily or when used as a chair, as the case may be, 25 as shown in Figs. 2 and 3. Associated with each wheel is a pair of supports 31, 32, which, when in supporting position as shown in Fig. 2, extend, one in front of, and the other to the rear of the perambulator wheel, thus providing with the wheel, a three-point contact support. These supports are inside of the wheels so that the three contact points are not in a straight line. By this construction a firm support in 30 a forward and back direction is provided, and the lateral support is likewise extremely efficient. As a result, not only is the device held stationary, but, in addition, there is little or no danger of its toppling over. 35 Support 31 is pivoted to the brace 9 at 33, and support 32 is pivoted to the brace at 34. Links 35 and 36 are hingedly connected to supports 31 and 32, as at 37, 38. Links 35 and 36 are curved to meet a common point, and the links on either side are connected at these common points by a rod or bar 39. It will be apparent that if the bar 39 is moved downward, links 35, 36 will cause the supports 31, 32 to fold upwardly to the position shown in Fig. 1, and on the other hand, if bar 39 is moved upwardly supports 31, 32 will be swung down into supporting position. The means for operating the bar 39 is clearly shown in 50 Fig. 4. Riveted to the bar 39 is a yoke 40. A link 41 is pivoted to the bar 39 on one side of the yoke 40 and at its upper end is pivotally connected to a lever 42. A strap 43 is secured to the link 41 on the other side of the yoke 40, at 44, and the upper end of this strap 43 and also the upper end of the link 41 are pivotally connected to the lever 42 at 45. The strap 43 and link 41, being on opposite sides of the 55 yoke 40, keep the latter from tipping or

getting out of alignment in operation. Lever 42 is fulcrumed at a lug 46 on the upright 8. At the other end of the lever is a knob or handle 47 for convenience in operation. It will be apparent that the upward or downward movement of the bar 39 is effected by an upward or downward movement of the lever 42. In order to lock the lever in its upper position in which the legs are supporting the device, a catch 48 is provided. Lever 42 rests in this catch and consequently the supports 31, 32, cannot be moved out of supporting position until the lever is raised above and away from the catch. 75

It will be noted that the handle 47 is in close proximity to the propelling handle 10 so that the operator may readily move the supports into or out of supporting position without removing both hands from the 80 handle 10. Furthermore as the operating means move substantially within the limits of the framework there is no part projecting out from the device, the objections to which are obvious. 85

When it is desired to utilize the device as a high-chair, the supports are moved into supporting position as above described, and the chair member is removed from its lower position and is hung upon the upper cross-bar 11. On each upright 7 is a bracket 29, and on each side of the seat 19 at the forward part thereof is a hook-like member 30. When the chair member is in its upper position (Fig. 2) this member 30 95 embraces the upright 7 and rests upon the bracket 29, thereby providing support for the forward part of the seat. As the supports may be moved into or out of supporting position while the device is being used 100 as a high-chair, it may be readily wheeled up to or away from a table or about the house and again made stationary without removing the child. 105

When the device is used as a chair a tray 110 49 may be used in connection with the chair member to serve both as a support for toys and the like and as a means for preventing the child from falling out. The tray 49 has arms 50 which rest on the chair arms 22 and 115 51 at the end of the arms 50 are hooks 51 by means of which the tray may be hooked on the cross-bar 11 as shown in Fig. 2.

For purposes of transportation or the like, the chair member may be readily and compactly packed within the framework. The back 26 is swung upward on the pivot until it is substantially parallel with the seat and then the yokes 27 may slide on the pins 27^a until the back 26 rests on the arm 22. The 120 125 chair member may then be placed in the framework, the seat being parallel with the rear thereof, and is held in place by resting in the transverse brace 13.

It will be seen from the above description 130

that we have provided a perambulator in which in this particular form the seat with its back, arms and foot-rest is a unified structure, removable from the framework of the device and quickly and readily placed in upper or lower position, and further, that we have provided efficient means for supporting the device in a stationary position, and such that the supporting members may 5 be easily placed in operative or inoperative position and may be used at any time irrespective of the position of the chair, so that the perambulator may be used with high or low seat, or as a high or low chair, as desired. It will also be observed that the wheels are of large diameter, thus enabling the device, even though loaded, to be easily pushed or pulled over obstructions without lifting and without undue shocks and jars to 10 the occupant or operator; also that the single pair of wheels are substantially centrally located with respect to the front and rear of the device so as to properly carry the load without imposing excessive burden on the 15 operator when wheeling it about, and whereby larger wheels can be employed without projecting unduly beyond the forward and rearward limits of the frame-work, and the frame can be tipped to the rear for ready 20 operation in its use as a perambulator. When the device is to be stationary the legs are thrown down in front of and to the rear of the wheels an appreciable distance so that 25 it is impossible for the child to tip over in it, even when used as a high chair, and even though the child should lunge forward or 30 backward as it is apt to do.

Our invention is thus intended as a perambulator which may be readily wheeled 40 about out of doors, or allowed to remain in a standing stationary position, or folded up into compact form for bodily transportation. At the same time it possesses those features 45 of construction permitting its use as a high chair, an article of furniture not found in many places where a child is apt to be taken, and when so used of movement about without removing the occupant.

Having thus described our invention what 50 we claim as new and desire to secure by Letters Patent is:—

1. A child's perambulator comprising a light skeleton vertically elongated frame, a pair of large perambulator wheels located 55 substantially at the middle of the lower end of said frame, a handle at the upper end of said frame for the operation, movement and handling of the perambulator, a seat between the upper and lower ends of the 60 frame, a prop member pivotally mounted on the lower end of said frame forward of the axis of said wheels, said prop member being pivoted intermediate its length and having a portion movable about said pivot from 65 a position in which it extends downwardly and forwardly to act as a prop to a position in which it extends upwardly from said pivot, said member having an arm extending in a different direction from said pivot from the direction in which said prop portion 70 extends, a second prop member pivotally mounted on the lower end of said frame rearward of the axis of said wheels, said second prop member being pivoted intermediate its length and having a portion movable about said pivot from a position in which it extends downwardly and rearwardly to act as a prop to a position in which it extends upwardly from said pivot, said second prop member having an arm extending in a different direction from said pivot from the direction in which said prop portion 75 extends, and means acting on said arms for moving said prop members from their first to their second positions, said means being operable from a position at the rear of the elongated frame.
2. A child's perambulator comprising a light skeleton vertically elongated frame, a pair of large perambulator wheels at the lower end of said frame, a handle at the upper end of said frame for the operation, movement and handling of the perambulator, a seat between the upper and lower ends of the frame, a prop member pivotally mounted on the lower end of said frame forward of the axis of said wheels, said prop member being pivoted intermediate its length and having a portion movable about said pivot from a position in which it extends downwardly and forwardly to act as a prop to a position in which it extends upwardly from said pivot, said member having an arm extending in a different direction from said pivot from the direction in which said prop portion 90 extends, a second prop member pivotally mounted on the lower end of said frame rearward of the axis of said wheels, said second prop member being pivoted intermediate its length and having a portion movable about said pivot from a position in which it extends downwardly and rearwardly to act as a prop to a position in which it extends upwardly from said pivot, said member having an arm extending in a different direction from said pivot from the direction in which said prop portion 95 extends, and means acting on said arms for moving said prop members from their first to their second positions, said means being operable from a position at the rear of the elongated frame.
3. A child's perambulator comprising a light vertically elongated frame, a handle near the upper end of the frame for operation movement and handling of the perambulator, a movable seat, means for supporting said seat near the lower part of said frame, means for supporting said seat near the upper part of said frame when it 100

is desired to use the device as a high-chair, a pair of large perambulator wheels at the lower end of the frame, two props movably mounted at the lower end of the frame, one 5 having a portion for engaging a supporting surface in the rear of said wheels and the other having a portion for engaging a supporting surface in front of said wheels, and means for moving said props from supporting 10 to non-supporting positions, said means being operable from a position at the upper end of the elongated frame.

4. A child's perambulator comprising a light skeleton frame, a handle near the upper end of the frame for operation, movement and handling of the perambulator, a movable seat, means for supporting said seat near the lower part of said frame, means for supporting said seat near the upper part of said frame when it is desired 20 to use the device as a high-chair, the seat in both of said positions extending in substan-

tially the same general direction and with the back of said seat at the rear of the frame, a pair of large perambulator wheels 25 at the lower end of the frame, two props movably mounted at the lower end of the frame, one having a portion for engaging a supporting surface in the rear of said wheels, and the other having a portion for 30 engaging a supporting surface in front of said wheels, and means for moving said props from supporting to non-supporting positions, operable from a position adjacent said handle.

In witness whereof, we have hereunto subscribed our names in the presence of two witnesses.
